(57) **CLAIM**

We claim the ornamental design for a gas range burner grate, as shown and described.

DESCRIPTION

FIG. 1 is a front perspective view of a gas range burner grate showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion shown in FIG. 6;

FIG. 9 is an enlarged view of the encircled portion shown in FIG. 6;

FIG. 10 is a front perspective view thereof shown in an example environment;

FIG. 11 is an exploded front perspective view thereof shown in an alternate configuration; and,

FIG. 12 is a front perspective view thereof shown in the alternative configuration.

The broken lines in FIGS. 1 through 7, FIGS. 9 and 11 to 12 depict portions of the gas range burner grate that form no part of the claimed design, and the broken lines in FIG. 10 depict environmental subject matter that forms no part of the claimed design.

The dot-dash broken lines encircling portions of the claimed design that are illustrated in enlargements form no part of the claimed design.
